CLAIM

The ornamental design for an audible bandage container, as shown and described.

DESCRIPTION

FIG. 1 is a shaded front elevation view of an audible bandage container showing our new design;

FIG. 2 is a shaded rear elevation view thereof;

FIG. 3 is a shaded top plan view thereof;

FIG. 4 is a shaded bottom plan view thereof;

FIG. 5 is a shaded right elevation view thereof;

FIG. 6 is a shaded left elevation view thereof;

FIG. 7 is a shaded first perspective view thereof with the audible bandage container in a closed configuration;

FIG. 8 is a shaded second perspective view thereof with the audible bandage container in the closed configuration;

FIG. 9 is a shaded third perspective view thereof with the audible bandage container in a first opened configuration;

FIG. 10 is a shaded fourth perspective view thereof with the audible bandage container in the first opened configuration;

FIG. 11 is a shaded fifth perspective view thereof with the audible bandage container in a second opened configuration; and

FIG. 12 is a shaded sixth perspective view thereof with the audible bandage container in the second opened configuration;

FIG. 13 is an unshaded front elevation view of an audible bandage container showing our new design;

FIG. 14 is an unshaded rear elevation view thereof;

FIG. 15 is an unshaded top plan view thereof;

FIG. 16 is an unshaded bottom plan view thereof;

FIG. 17 is an unshaded right elevation view thereof;

FIG. 18 is an unshaded left elevation view thereof;

FIG. 19 is an unshaded first perspective view thereof with the audible bandage container in a closed configuration;

FIG. 20 is an unshaded second perspective view thereof with the audible bandage container in the closed configuration;

FIG. 21 is an unshaded third perspective view thereof with the audible bandage container in a first opened configuration; FIG. 22 is an unshaded fourth perspective view thereof with the audible bandage container in the first opened configuration;

FIG. 23 is an unshaded fifth perspective view thereof with the audible bandage container in a second opened configuration; and,

FIG. 24 is an unshaded sixth perspective view thereof with the audible bandage container in the second opened configuration.

The dashed lines are included for the purpose of illustrating portions of the audible bandage container that form no part of the claimed design.
